METHOD AND MEANS FOR COLORING AND
COATING WIRES AND THE LIKENeil C. Lamont, Edgeworth, Pa., assignor to
National Electric Products Corporation, New
York, N. Y., a corporation of Delaware

Application October 28, 1930. Serial No. 491,706

12 Claims. (Cl. 91—68)

This invention relates to a method and a machine for coloring insulating wire and the like and thereafter coating it with a thin coating of wax-like material such as paraffin.

5 The invention will be described with reference to the making of certain types of insulated wires, although it will be understood that the machine and the steps of the method which are employed may be used in the making of other articles where 10 similar problems arise.

One desirable form of insulated wire includes a braided covering which may serve as a wrapping for other interior insulation. Such braiding may be directly colored or it may be first impregnated with an impregnating material such as 15 stearin pitch or some similar flame retardent compound and after it is impregnated it may be colored.

In some cases the impregnated braided covering 20 is first dusted with mica or a like powdery material before the color is applied. Over the color coating it is desirable to provide a thin super-coating of a wax-like material to provide a slick or non-stick outer finish. In other cases the 25 impregnated wire is directly covered with the wax-like super-coating, the intermediate color coat being omitted.

In the manufacture of insulated wires of the kind described above, it has been found that the 30 wax-like material of the finish coat may tend to excessively blend or merge with the underlying coatings and with the impregnating compound. When colors are used, this blending tends to 35 destroy the brilliancy of the color coating and produce a wire having a muddy or flat appearance. This blending and merging is extremely liable to occur if the final waxing step be carried out by dipping the previously impregnated 40 wire in a bath of molten wax so that the heat of the bath would tend to remelt the underlying material. Such undesired blending or merging also tends to occur if excessive quantities of molten wax were applied in any way to the insulated 45 wire. The application of excessive quantities of wax over a color coating is also undesirable. Accordingly, with various kinds of insulated wires it is a desideratum to apply a regulated and desired minimum quantity of wax and to also apply the wax in such manner that the wax does not 50 successively blend or merge with underlying material and to further apply this wax-like material in such a way that the use of supplementary scrapers or wiping dies or the like to remove excessive wax may be dispensed with.

55 It is further desirable that the steps of color

coating of the wire and afterwards coating it with wax may be carried out in one continuous process, a color coating being first applied and the wax-like material being subsequently applied in the proper manner to secure the desired final 6 product.

The present invention has for one of its objects the provision of a novel method and machine for applying one or more color coats to insulated wires or like articles and for thereafter applying over such coloring a thin wax-like covering. 65

Another object of the present invention resides in the provision of a novel method and machine for applying super-coats of wax-like material in 70 such a way that the object being coated will not come in contact with an excessive quantity of heated wax-like material and also in the provision of a method in which regulated quantities of the super-coating may be applied. 75

A further object of the present invention resides in the provision of a method and machine for applying wax-like material to articles to be coated with a thin super-coating of wax-like material and in which such material is applied to the 80 article in the form of a mist.

Further and other objects of the present invention will be hereinafter set forth in the accompanying specification and claims and shown in the drawings which by way of illustration show 85 preferred embodiments of the apparatus adaptable for carrying out the novel method.

In the drawings:

Figure 1 shows somewhat diagrammatically the steps of the method beginning with the uncolored wire, carrying the wire through the coloring step or steps, carrying it through the drying steps and thence through the waxing step; 90

Fig. 2 is a central sectional view of the wax applying pot and waxing apparatus. In this embodiment the wire passes vertically through the waxing pot; 95

Fig. 3 is a top plan view of the waxing pot, certain parts being shown in section, the view being taken substantially on lines 3—3 of Fig. 2; 100

Fig. 4 is a view of a different embodiment of waxing pot wherein only two atomizing jets are provided instead of the four which are shown in the preceding Figs. 2 and 3. Also in this form of waxing pot the wire is adapted to traverse through the pot in a horizontal direction instead of in a vertical direction; 105

Fig. 5 is a detail view of one of the leather washers which are used for the inlet and outlet orifices 110

of the waxing pot and this figure also shows the retaining means for the washer;

Fig. 6 is a modified form of waxing pot adapted for waxing wire and traversing it horizontally through the pot and wherein any four jets may be employed instead of the two jets shown in Fig. 4; and

Fig. 7 is a more complete view of the apparatus which is capable of carrying out the method and shows in further detail the various driving means, pay-out and take-up reels, etc.

Referring first to Figs. 1 and 7, the part designated 10 in Fig. 7 comprises the pay-out reel. This reel has wound upon it the insulated wire after it has been braided and impregnated if the wire is of the impregnated kind. 11 designates the wire which is led off from the pay-out reel and this wire extends upwardly into a drying tower which receives heated air at the top so as to thoroughly dry the wire traversing therethrough. Adjacent the top of the drying tower the wire 11 passes over a flanged pulley 12. After passing over this flanged pulley the wire 11 again is directed downwardly to a painting apparatus generally designated 13. This painting apparatus is provided with an inlet orifice 14 to permit the wire 11 to enter the paint pot and within the paint pot the wire 11 passes down below the surface of the paint and over a free running pulley 15 which is indicated in dotted lines in Fig. 7. After passing over the pulley the wire which has then received one coat of paint passes upwardly out of the paint pot 13 and is drawn past a wiping nipple 16. The wire emerging from this wiping nipple 16 has the first coat of color applied thereto and this wire will be designated 11a signifying that it has been colored with one coat of paint. Wire 11a again traverses upwardly into the drying tower where the coat of paint is thoroughly dried and in the upper part of the drying tower, wire 11a passes over a second pulley 12a thereafter returns downwardly again and enters the paint pot a second time. The wire enters through a similar aperture and passes over a similar pulley as that previously described. 11b designates the wire which has left the paint pot after it has received a second coat of paint. It will be appreciated that any number of coats may be applied. In some cases one coating will be sufficient, in which case one traverse of the wire through the paint pot will be omitted. In other cases more than two coats may be desirable, in which case additional traverses of the wire through the paint pot may be made. The wire 11b passes upwardly over a pulley 12b in the drying tower, being dried as before and thereafter this wire 11b again passes downwardly over a drying sheave or pulley 18 adjacent the lower part of the drying tower. After passing over this drying sheave, wire 11b again passes upwardly and over a fourth pulley 12c at the top of the drying tower. From 12c the painted and now thoroughly dried wire again passes downwardly over a capstan wheel 19. The wire leaving the capstan wheel will be designated 11c and such wire passes downwardly through the waxing pot generally designated 20 and out at the bottom over an idler pulley 21 (see Fig. 7), thence upwardly over another idler pulley 22 and finally downwardly to a take-up reel 23. The take-up reel and the capstan wheel are driven by any suitable driving mechanism from a main driving shaft 24 as indicated on Fig. 7.

The waxing pot will now be more fully described with reference to Figs. 2 and 3. The waxing

pot 20 comprises a tank of any suitable construction adapted to contain a quantity of molten wax or paraffin 25. For maintaining the paraffin in heated and molten condition suitable electrical heating devices 26 may be provided. The bottom of the tank 20 is provided with a stand pipe 27 which extends up above the level of the top of the paraffin in the bath and at its top this stand pipe is provided with an apertured leather washer 28. The purpose of the washer is to partially close up the aperture in the stand pipe and prevent excessive escape of the paraffin vapors from the waxing pot. The paraffin pot at the top is provided with a suitable cover 29 and this cover is provided with an inlet orifice for the entering wire, the orifice being partially closed by an apertured leather washer 28.

Fig. 5 shows in more detail one of the leather washers 28 secured in position by a spring clamped retainer 30. It will be understood that the leather washers 28 are removable so as to be replaced with other leather washers having different sized apertures when different sized wires are to be coated. In Fig. 2, 11c indicates the wire which traverses vertically through the waxing pot.

For applying the wax to the wire there are provided within the waxing pot a number of stand pipes 31. These stand-pipes extend upwardly substantially to the point indicated and adjacent the upper ends of the standpipes are atomizing nozzles generally designated 32. Air under pressure is admitted to the atomizing nozzles 32, the air being supplied by means of pipes 33 and the volume of air being adapted to be regulated by needle valves generally designated 34. When the waxing pot is in operation the blast of air which is directed to the atomizing nozzles draws up a quantity of molten paraffin from the bath 25 through the stand pipes 31. In the atomizing nozzles this molten paraffin is broken up into the form of a fine mist of molten paraffin and such mist is impinged by the jets upon the wire which traverses through the waxing pot. As shown in Fig. 3 there are four atomizing nozzles 32 so that the wire is acted upon by sprays of paraffin mist which impinge upon the wire in four directions. In this way the thin and uniform coating of wax is applied to the wire and excessive quantities of wax are prevented from being applied to the wire. Furthermore the arrangement is such that the wire at no time comes in contact with the molten paraffin in the bath nor is it subjected to excessive heat from the bath. In this way the undesired blending and merging of the wax of the underlying material is prevented.

Fig. 4 shows a slightly different embodiment adapted for coating a wire when the wire is traversed horizontally through the pot. In this figure only two atomizing jets 32 are provided.

In some cases where wire is traversed through the pot in a horizontal direction, it may be desirable to spray it from more than two sides. In such cases the arrangement shown in Fig. 6 may be provided. Here the paraffin pot 20a is of substantially hexagonal configuration to provide for the disposing of the atomizing jets 32 in the angular relation shown. This arrangement permits spraying the wire in more directions than two upon a horizontal traverse of the wire through the waxing pot.

It will be appreciated that any number of atomizing jets may be provided, but in practice four

have been found sufficient to provide for the desired uniformity of coating.

While the invention is described with reference to the application of wax, it also finds utility in the application of other like compounds to articles which are to be coated. By applying the compound in the form of a mist unreasonable overlapping of the compound or the application of excessive quantities of the compound to the article to be coated may be obviated.

The color compound used in the paint pot 13 may be that disclosed in Bockus Patent No. 1,765,000. Other desired colored paints may be used if desired.

15. What I claim is:

1. A machine for coloring insulated wire and applying a super-coating thereto comprising wire handling means for continuously advancing the wire, means for applying a color coating to the wire while it is in motion, and means for subsequently directing a mist of molten wax-like material upon the wire also while the wire is in motion and for avoiding excess heating of the wire during said wax application, so as to prevent impairment of the color coating, said wire handling means being adapted to advance the wire through the color coating means, from the color coating means through a drying space to the mist-directing means, and through the mist-directing means, in continuous succession and with maintained continuous motion of the same length of wire through the color coating means, the drying space and through the mist-directing means.

35. 2. A waxing pot for applying a super-coating of wax to insulated wire, comprising a container adapted to hold molten wax in its lower portion and having heating means for said wax, means for breaking up the said wax and directing a mist of the same above the level of the wax against an insulated wire passing vertically through the container, and standpipe means in the container opening outside the latter and extending up through the molten wax-containing portion to a point closely adjacent the point of application of the mist-directing means, for affording passage of the wire through the molten wax while avoiding excessive heating effect of the latter on the wire.

50. 3. A waxing pot for applying a super-coating of wax to insulated wire, comprising a container for hot molten wax and having heating means for said wax, means for withdrawing wax from the molten mass in the container, and for applying a mist of same to an insulated wire at a point out of the zone of heat of said molten mass, said means including a plurality of pairs of misting nozzles, each pair of nozzles being adapted to direct a mist of wax against diametrically opposite sides of the wire, and said pairs of nozzles being disposed for intersection, upon the wire, of their lines of mist application, each pair with the other, whereby the nozzles simultaneously each direct a mist of wax against a different side of the wire, and means associated with the container for maintaining the wire away from the heat of the hot molten mass therein, said last-mentioned means being constructed to afford passage of the wire through the mist-directing means while avoiding heating effects of the said hot molten mass on the wire.

75. 4. A waxing pot for applying a super-coating of wax to insulated wire, comprising a container for hot molten wax and having heating means for said wax, means for withdrawing wax from

the molten mass in the container and for applying a mist of same to an insulated wire at a point out of the zone of heat of said molten mass, and means associated with the container for restricting the zone of misting application of molten wax 80 on the wire and for maintaining the wire away from the heat of the hot molten mass in the container, said last mentioned means being constructed to afford passage of the wire past the mist-applying means while avoiding heating effects of the said hot molten mass on the wire.

5. A method of coloring and coating an insulated wire, comprising continuously advancing the wire, applying to said advancing wire liquid coloring material susceptible of having its coloring effect impaired by blending or merging with previously or subsequently applied coating or impregnating material, then drying the wire, and applying a super-coating to the same continuously advancing wire, by directing a mist of wax-like material on the wire and suppressing excessive heating effects on the wire while applying the wax-like material, so as to prevent blending or merging of the color coating and impairing the coloring effect thereof.

6. A method of coloring and coating an insulated wire, comprising continuously advancing the wire, applying to said advancing wire a color coating susceptible of having its coloring effect impaired by blending or merging with previously or subsequently applied coating or impregnating material, and applying a wax coating to the same continuously advancing wire by directing a mist of wax-like material on the wire so as to prevent blending or merging of the color coating and impairing the coloring effect thereof.

7. A method of coloring and super-coating an insulated wire, comprising applying thereto a coating of coloring material susceptible of having its coloring effect impaired by blending or merging with previously or subsequently applied coating or impregnating material, and thereafter applying a coating of wax-like material to the wire by impinging a mist of molten wax-like material thereon and by maintaining the wire 115 away from the heat of any substantial mass of said molten wax-like material while applying the coating of same, so as to prevent blending or merging of the color coating and impairing the coloring effect thereof.

8. A method of coloring and coating an insulated wire, comprising applying to the wire a color coating susceptible of having its coloring effect impaired by blending or merging with previously or subsequently applied coating or impregnating 130 material, and the step of providing a super-coating on the color coating by applying molten coating material thereon and suppressing heating effects of said molten material to avoid blending or merging of the color coating, said super-coating step including preventing blending or merging of the color coating and impairment of its coloring effect, by applying the said molten material in the form of a mist.

9. A method of coloring and coating an insulated wire, comprising applying to the wire liquid coloring material susceptible of having its coloring effect impaired by blending or merging with previously or subsequently applied coating or impregnating material, then drying the wire, and subsequently applying a coating of wax-like material to the wire over the dried coloring material and avoiding blending or merging of the latter and impairment of the coloring effect thereof, by maintaining the wire free of excess molten 145

wax-like material and away from the heat of said molten material, said method including effecting the coloring step, the drying step and the wax-coating step on the same wire while the latter is continuously advanced.

10. A method of coloring and super-coating an insulated wire, comprising continuously advancing the wire, applying to said advancing wire a coating of coloring material susceptible of having its coloring effect impaired by blending or merging with previously or subsequently applied coating or impregnating material, and thereafter applying to the same continuously advancing wire molten coating material to provide a super-coating on the color coating while preventing blending or merging of the latter, by maintaining the color-coated wire free of excess heated molten coating material and out of the zone of heat of said material when the said material is applied, so as to avoid impairing the coloring effect of the color coating by blending or merging of the latter with the said super-coating material or other material on the wire.

11. A method of coloring and coating an insulated wire, comprising coating the wire with coloring material susceptible of having its coloring effect impaired by blending or merging with previously or subsequently applied coating or impregnating material, and thereafter coating the wire with wax-like material and avoiding blending or merging of the coloring material on the

wire and impairment of the coloring effect thereof, by bringing the wire into contact with substantially only the amount of molten wax-like material required for the coating and maintaining the wire away from the heat of any substantial mass of said molten material.

80

12. The method of applying a super-coating of wax-like material to an insulated wire having thereon a coating susceptible of being impaired by blending or merging with previously or subsequently applied coating or impregnating material on juxtaposition with an excess of hot molten wax-like material at or above the melting temperature of the latter, which comprises applying a wax-like super-coating to the wire carrying the coating susceptible of blending or merging with previously or subsequently applied coating or impregnating material and preventing such blending or merging of the said coating with the wax coating, by applying the molten wax-like material in the form of a mist, and restricting the zone of misting application and maintaining the wire away from the zone of heat of any substantial mass of molten wax-like material, both prior to and immediately following the application of 100 said molten wax-like material in mist form, so as to prevent impairment of the underlying coating by blending or merging with said wax-like material.
